SMOKING APPLIANCE

Charles E. Stokes, 11580 La Maida St.,
North Hollywood, Calif. 91601

Filed June 30, 1969, Ser. No. 17,982

Term of patent 14 years

Int. Cl. D27—02

U.S. Cl. D85—8

FIG. 1 is a side elevational view of a smoking appliance, showing my new design;

FIG. 2 is an elevational view taken from the right-hand side of FIG. 1; and

FIG. 3 is a top plan view thereof.

I claim:

The ornamental design for a smoking appliance, as shown.
